UNITED STATES PATENT OFFICE.

FRANK H. HOBERG AND COMADORE C. THOMAS, JR., OF GREEN BAY, WISCONSIN.

SUCTION COUCH-ROLL.

1,159,381.

Specification of Letters Patent. Patented Nov. 9, 1915.

Application filed April 19, 1912. Serial No. 691,983.

To all whom it may concern:

Be it known that we, FRANK H. HOBERG and COMADORE C. THOMAS, Jr., citizens of the United States, residing at Green Bay, 5 county of Brown, and State of Wisconsin, have invented new and useful Improvements in Suction Couch-Rolls, of which the following is a specification.

Our invention relates to improvements in 10 couch rolls for paper making machines.

The object of our invention is to provide an improved suction couch roll in which the pressure will be evenly distributed over the whole width and length of that portion 15 of the roll which is covered with the carrier apron, and in which the moisture may be withdrawn without damage to the apron or to the formative portion of the paper sheet, and whereby damage to the apron from frictional contact with suction boxes may be 20 avoided.

In the drawings—Figure 1 is a diagrammatic view, illustrating our couch roll in its proper relation to the pulp receiving apron 25 of a paper making machine. Fig. 2 is an end view, part in section, of a couch roll embodying our invention. Fig. 3 is a front elevation, part in vertical longitudinal section, of a couch roll embodying our invention, the periphery of the couch roll being progressively broken away adjacent to the portion in section to show the manner in which the structure is built up. Fig. 4 is a detail sectional view of a portion of a couch 30 roll, showing a modified form of construction.

Like parts are identified by the same reference characters throughout the several views.

40 In Fig. 1, an apron A is illustrated in ordinary relation to a cylinder B, couch roll C, suction box or guide roll D and initial compression rollers E and F, the apron extending on the return side over the rollers 45 G, H, I, J and K. The member D may comprise the ordinary suction boxes or it may comprise a guide roll, since with our improved couch roll it is not essential that a suction box be used. All of the above 50 parts may be of any ordinary construction, except as to the couch roll, the specific structure of which will now be described.

Referring to Figs. 2 and 3, it will be observed that our improved couch roll is constructed with the cylinder 1 supported from 55

a tubular shaft 2 by radial tubular arms 3. The ends of the tubular shaft 2 are mounted in supporting bearings 5. At one end the shaft 2 extends through the bearing member 5, and is connected with a suction pipe 7. 60 A coupling 8 allows shaft 2 to rotate independently of suction pipe 7.

The cylinder 1 is provided with annular flanges 9 on its periphery which support an annular series of rods 10, the ends of which are received in flanged collars 11. This series of rods 10 is covered by coiled wire 14 which is preferably wound around the cylinder in a helical coil, and is covered by wire netting 15. The wire netting 15 is jacketed 70 with a heavy felt covering 16, the ends of which are preferably turned inwardly at 17 and engage between the flanged collar 11 and a clamping collar 19 which is bolted at 20 to the head piece 21. The flanged collar 75 11 has screw threaded engagement with this head piece and the ends of the cylinder 1 are mounted on inturned head flanges 23.

With the above described construction, it will be observed that the jacket or peripheral felt covering of the couch roll is supported from the cylinder 1 by the flanges 9 and rods 10, together with the coiled wire 14 and wire netting 15 which coöperate to prevent the felt covering or jacket from being depressed into the spaces between the rods 10. There is, therefore, an annular open space between the cylinder 1 and the jacket 16, unobstructed except by the flanges 9, rods 10 and the wire coil and net. The 80 flanges 9 are provided at intervals with apertures 26 which allow water to flow along the surface of the cylinder 1 to the tubular radial arms 3. The tubular arms 3 therefore serve the triple purpose of supporting 85 the cylinder 1 from the tubular shaft 2, of providing drainage for the space between the cylinder 1 and the outer jacket, and of extending the vacuum produced by suction exerted through the pipe 7 into said space. 90

The heavy jacket 16, which forms the periphery of the roll, so far obstructs the passage of air into the space between it and the cylinder 1 that a sufficient suction will be maintained through that portion of the periphery of the roll which is covered by the apron or carrier A, as shown in Fig. 1. The water will therefore be withdrawn from the pulp sheet through the apron A and through the jacket 16 into the annular suction space 110 100 105 110

of the couch roll, and from this space it will be drained through the radial tubes 3 and tubular shaft 2 to the pipe 7.

The construction shown in Fig. 4 is the same as that shown in the other views, except at the ends of the couch roll and within the tubular shaft 2. In Fig. 4, the shaft 2 is provided with rotary cylindrical valves 30, having ports 31 adapted for registry with radial tubular arms 3^A. The valves 30 are also provided with ports 32 in position for registry with one of the arms 3^A. One of these valves 30 is actuated by a rod 35 and the other valve 30 is actuated by a sleeve 10 rod 36, through which rod 35 may extend in order that both rods may be actuated from the same end of the roll.

The flanges 9^A on the cylinder 1 adjacent to the ends of the cylinder extend outwardly from the cylinder a little farther than the flanges 9 and are notched to receive the rods 10 to such a depth that the wire and felt coverings may bear directly on the peripheries of the flanges 9^A. These flanges 9^A 20 have no openings corresponding with the openings 26 in the flange 9 and it therefore follows that said flanges 9^A constitute substantially complete partitions for the space between the cylinder 1 and the outer coverings, subdividing said space into annular cavities 38 and 39 respectively at each end of the roll. When the cylindrical valves 30 are rotated to closed position, the air will not be exhausted from the spaces 38 and 39. 25 By rotating the valves 30 until the opening 32 is in registry with the inner tube 3^A, the vacuum will be extended to the cavity 39, and by rotating the valves 30 until the openings 31 are in registry with the tubular arms 3^A, the vacuum will be extended to both cavities 38 and 39. In this manner, we are enabled to increase or diminish the length of the suction area of our couch roll. 30 When running narrow strips of paper, the valves will be rotated to cut off the suction from cavity 38, or from cavities 38 and 39. For example, assuming that the strip of paper is of a width substantially equal to the distance between the inner flanges 9^A, the valves will be adjusted to 35 cut off the suction from both cavities 38 and 39, while if the strip is of a width equal to the distance between the outer flanges 9^A, the valves 30 will be adjusted to 40 cut off the suction from the cavities 38, ports 32 of the valves being in registry with the cavities 39 to permit the vacuum to extend thereto. It will of course be understood that any desired number of these independent annular cavities may be provided and the suction applied or cut off by means of suitable valve mechanism.

The valves 30 are preferably provided with segmental guide channels 40 into which 45 stop projections 41 may extend from the tu-

bular shaft 2, whereby the rotative movement of the valves 30 may be limited.

We claim—

1. A suction couch roll comprising a cylinder, a jacket adapted to absorb moisture by capillary attraction and by suction, encircling said cylinder and spaced therefrom, crossed reinforcing members supporting said jacket from the cylinder at all points and adapted to prevent the formation of hollows or channels in the outer surface of said jacket, said cylinder being provided with a suction duct leading from the space between the cylinder and jacket. 75

2. A suction couch roll comprising a closed cylinder provided with annular peripheral ribs, an annular series of jacket supporting rods mounted on said ribs, a netted covering for said rods, a jacket of non-metallic absorbent material inclosing the netted covering and forming the periphery of the roll, and means for applying suction to the space between the jacket and cylinder. 80

3. A couch roll consisting of the combination of a tubular shaft, a closed cylinder supported by said shaft, tubular radial arms communicating between the interior of the shaft and space exterior to the periphery of said cylinder, a series of annular apertured ribs mounted upon the periphery of said cylinder, a series of rods connected with the cylinder at their respective ends and having their intermediate portions supported by said ribs, a perforate metallic covering for said rods and a felt jacket mounted upon said metallic covering and held in cylindrical form thereby. 90

4. A suction couch roll provided with a jacketed periphery, of absorbent material, means for supporting said jacket in true cylindrical form, said roll having an annular suction cavity immediately underneath said jacket. 105

5. A suction couch roll comprising a closed cylinder, a set of annular ribs encircling said cylinder at spaced intervals and having outwardly converging walls, sets of rods superposed with those of one set crossing those of the next set, the rods of the successive sets being progressively smaller in diameter and greater in number and in proximity to each other, a jacket composed of nonmetallic fabric encircling the outer set of rods, and means for applying suction to the space between the jacket and the cylinder, said outer sets of crossed rods being of such size and arranged in such proximity as to form a substantially continuous support for said covering while exposing substantially the entire covering encircling said cavity to the suction applied through said cavity. 110

6. A suction couch roll comprising a cylinder, an absorbent covering for the cylinder, spaced therefrom, means for with- 120

130

drawing fluid from the space between the cylinder and covering, and a set of annular partitions subdividing said space.

7. A suction couch roll comprising a cylinder, a covering for the cylinder spaced therefrom and composed of metallic and nonmetallic layers, annular partitions subdividing the space between the cylinder and covering, and means for withdrawing fluid from some of said subdivisions independently of the others.

8. A suction couch roll comprising a cylinder, a supporting tubular shaft, suction tubes extending radially from the shaft to

the cylinder, a peripheral jacket of non-metallic absorbent material encircling the cylinder and spaced therefrom, valves in the shaft adapted to close and open communication with some of said suction tubes, and annular partitions subdividing the space between the cylinder and jacket.

In testimony whereof we affix our signatures in the presence of two witnesses.
